(57) **CLAIM**

The ornamental design for an one piece RV rain gutter extension, as shown and described.

DESCRIPTION

FIG. 1 is a top, right front perspective view of an one piece RV rain gutter extension embodying my design;

FIG. 2 is a front side elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a back side elevational view thereof;

FIG. 8 is a top, left front perspective view of another one piece RV rain gutter extension embodying my design;

FIG. 9 is a front side elevational view of the same one piece RV rain gutter extension as in FIG. 8;

FIG. 10 is a right side elevational view thereof;

FIG. 11 is a left side elevational view thereof;

FIG. 12 is a top plan view thereof;

FIG. 13 is a bottom plan view thereof; and,

FIG. 14 is a back side elevational view thereof.
